(57) CLAIM

The ornamental design for an electric violin, as shown and described.

DESCRIPTION

FIG. 1 is a front, top and right side perspective view of an electric violin showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken line that appears on the upper, right side of the electric violin body in FIGS. 1, 3, and 5 represents an unclaimed cut line and forms no part of the claimed design.

1 Claim, 4 Drawing Sheets

FIG. 1

FIG. 2

FIG. 3

FIG. 4

FIG. 5
